UNITED STATES PATENT OFFICE.

GEORGE F. CRUMBAUGH, OF ST. LOUIS, MISSOURI, ASSIGNOR OF ONE-HALF TO EDWIN W. GROVE, OF ST. LOUIS, MISSOURI.

VENeer LATH.

1,107,907.

Specification of Letters Patent. Patented Aug. 18, 1914.

Application filed May 7, 1913, Serial No. 766,220. Renewed February 16, 1914. Serial No. 819,071.

To all whom it may concern:

Be it known that I, GEORGE P. CRUMBAUGH, a citizen of the United States, residing at St. Louis, in the State of Missouri, have invented new and useful Improvements 5 in Veneer Laths, of which the following is a specification.

This invention relates to veneer laths for wall covering or other building purposes, 10 and the primary object of the invention is to provide a lath made up of a plurality of veneer strips of suitable length fixed at intervals to space blocks or spacing devices and to have the strips primarily separated 15 to form key ways for a plaster covering.

A further object of the invention is to provide a lath composed of veneer strips held in fixed spaced relation and wherein the strips are disposed at an angle so as to 20 produce key openings that will have the best effect in positively securing a plaster covering applied over the lath and securely hold the plaster covering in different directions or to resist weight strain both vertically and 25 transversely and thus prevent cracking and falling away of the plaster covering from the improved lath.

The improved laths may be either angularly disposed relatively to a horizontal 30 plane or they may be arranged horizontally straight, and in some instances it is desirable or preferred that the laths be alternately arranged so that the angular strips thereof will be in reverse positions and give a 35 greater resistance to cracking or displacement of the plaster covering, especially on ceilings. When the laths are applied the edges are exposed at the front and the flat sides of the strips comprised in the lath organizations form the walls for the keys. 40

Another feature of the improved lath is that they may be telescoped at the ends and thereby rendered adjustable to accommodate variations in the distance apart of studding 45 and be secured by any suitable fastening means extending thereover at the joint and against a stud, or simply fastened with a large headed nail.

Among other advantages of the improved 50 lath are that it can be used on a flat surface, narrow spaces and strips and may be applied more expeditiously than common wood lath because of the increased width.

In the drawing: Figure 1 illustrates a 55 perspective view showing the improved

lath applied and illustrating the strips of the laths as disclosed at an angle to a horizontal plane and the angles of adjacent strips in reverse positions. Fig. 2 is a view similar to Fig. 1 showing the laths composed of strips at angles to a horizontal plane and the strips of adjacent laths in the same angle relatively to each other. Fig. 3 is a view similar to Figs. 1 and 2 showing the lath composed of horizontally straight strips. Fig. 4 is a transverse vertical section taken in the plane of the line 4—4, Fig. 1. Fig. 5 is a front elevation of a portion of the lath as shown by Fig. 1.

The numeral 5 designates a studding arranged as usual, and it will be understood that in the erection of a wall to which the lath is applied the same organization of framing will be adopted as now commonly pursued. The improved lath, however, is not limited in its application to studding as it may be placed against a smooth surface, such as a partition, or against studding in strips at corners, or disposed in very small spaces or corners with equal efficiency.

In the arrangement of the improved lath as shown by Figs. 1, 4 and 5, each lath 6 is composed of a plurality of veneer strips 7 arranged at an angle to a horizontal plane and separated equal distances by space devices 8. While it is preferred to use veneer strips 7 and blocks 8 in the organization of the lath, it will be understood that similar strips might also be associated with any other spacing device adapted for the purpose and suitably secured to the strips. Whatever may be the organization of the strips and space devices, the ends of the strips at the opposite extremities of the lath are extended beyond the nearest series of 95 space devices so that the extremities of contiguous laths may be telescopically interfitting as at 9, the laths thus being rendered adjustable to compensate for variations in the distance between studding as often occurs in rapidly erected building structures.

The laths are arranged edgewise against the studding or other supporting means therefor, and when the ends of the laths are joined or interfitted, as shown by Fig. 1 for 100 instance, a securing strip, such as a twisted wire or other analogous device 10, is applied thereover and nailed or secured by fastenings 11 which are driven through the wire or securing strip and also through 110

spaces of the laths, and when this securing wire or strip is applied over the jointed ends of the laths, a very firm and reliable application of the laths results.

5 As shown by Fig. 2, the laths may be so applied that the strips 7 throughout the whole series of laths may have the same angle of inclination relatively to a horizontal plane or all be in the same angle. It will be found, however, very advantageous to arrange the laths as shown by Fig. 1 and wherein the laths are alternately disposed so that the strips 7 thereof will be at reverse angles; and by this means a superior key organization is produced that will be a decided advantage in holding the plaster covering 12, as shown by Fig. 4, in association with the laths and prevent cracking and loosening of any part of the covering and also more positively oppose any tendency of the weight strain of the plaster covering to fracture.

In the form of the lath as shown by Fig. 3 the veneer strips 13 are spaced through the medium of space devices 14, but the strips are horizontally straight. While this form of the lath has been found practicable for many uses, it is not as positive in its action as the form of lath first described.

30 In all the forms of the lath as shown, the edges of the strips are exposed and the flat sides of the strips produce the walls for the keys that are formed by the exposed key openings, thus providing a strong structure and at the same time forming a more positive key producing means, particularly as compared to the ordinary flat lath which gives a considerable exposure of lath body with a comparatively small and impositively operating key opening.

The preferred method of manufacturing the improved lath is to build a stack of alternate layers of sheets of veneer and sticks extended across the width of the sheets of veneer, the whole being glued preferably with waterproof glue. The sheets of lath are then cut off to form the strips by any suitable mechanism and the sticks are simultaneously cut therewith. The lath will be made in lengths to cover three or four studs, the preferred length being about fifty-two inches. The additional length of the

improved lath as compared with the usual length of wood lath provides for the telescopic association of the ends of the laths 55 and an adjustment thereof to accommodate irregularity of spacing of studs. If desired the lath may be increased or decreased in width and length and other modifications in the details within the scope of the invention 60 may be adopted to accommodate various applications or uses of the improved lath.

What is claimed is:

1. A lath consisting of a plurality of thin strips having their flat sides arranged 65 in parallel relation and held in fixed spaced association to provide exposed edges with openings therebetween to form key ways for a plaster covering.

2. A lath consisting of a series of thin strips and spacing devices between the same, the strips having their flat sides arranged in superposed relation and their edges exposed for the reception of a plaster covering, the strips being disposed at an angle 75 to a horizontal plane.

3. The combination of laths consisting of thin strips arranged with their flat sides in superposed relation and provided with means for holding them fixed distances 80 apart, the opposite extremities of the strips of adjacent laths being telescoped with relation to each other and adjustable, and means for securing the laths in applied position.

4. The combination with a wall or other support, of a series of laths each comprising a plurality of thin strips having their flat sides in superposed relation and their edges exposed for the application thereto of a plaster covering, the strips being provided with devices to hold them in fixed spaced relation, the strips being at an angle to a horizontal plane and the adjacent laths having their strips at reverse angles, and means for securing the laths to the wall or other support.

In testimony whereof I have hereunto set my hand in presence of two subscribing witnesses.

GEORGE P. CRUMBAUGH.
